UNITED STATES PATENT OFFICE

2,476,556

STRETCH-BENDING MACHINE

Paul F. Maize, Detroit, Mich., assignor to Briggs Manufacturing Company, Detroit, Mich., a corporation of Michigan

Application April 14, 1945, Serial No. 588,324

6 Claims. (Cl. 153—48)

1

This invention relates to stretch-bending machines and more particularly to machines adapted to simultaneously bend and stretch relatively long metal strips or workpieces, especially strips of irregular cross-section.

An object of the present invention is to provide an improved machine for bending or forming and at the same time stretching an elongate metal section to a desired contour or shape, such as of three or more dimensional curvature.

A further object of the invention is to bend or form in improved manner by a bending and stretching operation a metal strip of angular cross-section into longitudinally irregular contour in which all bent portions of the strip, after the operation has been completed, do not lie in a single plane.

More specifically an object of the invention is to bend an elongate metal strip over a suitably shaped die while at the same time stretching the strip and causing it to conform to the longitudinal configuration or contour of a groove or channel in said die.

Still another object of the invention is to provide a mechanism for bending a metal strip over a die and simultaneously exerting tension on the strip to draw or force it into a groove, channel or the like of irregular longitudinal configuration in the die thereby permanently shaping the strip to the contour of the die and also to the longitudinal configuration of the groove or channel.

A further object of the invention is to provide a relatively compact, easily operable and efficient mechanism for accomplishing the foregoing purposes, and in particular to provide a construction and arrangement of the operating mechanism by which the overall length of the machine and the space occupied by the machine may be materially reduced.

Other objects of this invention will appear in the following description and claims, reference being had to the accompanying drawings forming a part of this specification wherein like reference characters designate corresponding parts in the several views.

Fig. 1 is a fragmentary perspective view of a combined bending and stretching apparatus constructed in accordance with one embodiment of the present invention.

Fig. 2 is a fragmentary perspective view looking towards one end of the machine illustrated in Fig. 1.

Fig. 3 is a plan view of the forming die.

Fig. 4 is an end elevation taken substantially from lines 4—4 of Fig. 3 looking in the direction of the arrows.

Fig. 5 is a diagrammatic view showing a hydraulic circuit by means of which the hydraulic mechanism is operated for forming and stretching the workpiece on the forming die.

Fig. 6 is a diagrammatic view showing the pneumatic circuit by which the work clamps are controlled.

Before explaining in detail the present invention it is to be understood that the invention is not limited in its application to the details of construction and arrangement of parts illustrated in the accompanying drawings, since the invention is capable of other embodiments and of being practiced or carried out in various ways. Also it is to be understood that the phraseology or terminology employed herein is for the purpose of description and not of limitation.

In the drawings there is illustrated, by way of example, one embodiment of the present invention in the form of a machine or apparatus for bending or forming an elongate metal strip, angular in cross-section, to the desired contour, the construction and operation being such that the strip will be bent in its length in more than two directions as determined by the longitudinal configuration of a groove or channel in the die, thereby permanently forming portions of the strip so as to lie in different planes. The illustrated machine comprises an upright frame 10 upon which is supported a horizontal bed 11. The frame preferably comprises laterally spaced vertical side members 10a and 10b providing a space therebetween for the operating mechanism as hereinafter described. Mounted upon the bed and adjustable longitudinally thereon are a pair of spacer blocks 12 and 13 which rigidly support a forming and stretching die 14 having the upper surface thereof crowned or otherwise curved in accordance with the desired contour to be imparted to a metal strip or elongate workpiece 15. In the present instance, as shown in Fig. 4, the metal strip 15 to be bent or formed is angular in cross-section. However, it will be understood that the particular cross-sectional shape of the workpiece may vary from that herein illustrated.

As illustrated particularly in Figs. 3 and 4, the metal strip 15 is drawn into and formed within a groove or channel 16 cut in the upper surface of the forming die 14 and extending from end to end thereof. This groove or channel in the present embodiment of the invention, illustrated by way of example, is shown as sinuous or serpentine in shape. In other words, the forming groove or channel 16 has an irregular longitudinal configuration with non-parallel sides, and as a consequence the strip or workpiece 15, when drawn down or stretched over the upper surface of the die and forced into this groove or channel, will have an irregular longitudinal configuration. As will be seen, the workpiece or strip will be bent by the forming die in three or more directions to a desired contour or shape of three or more dimensional curvature. The forming channel or groove 16 has upwardly and outwardly inclined

or tapering sides and is shaped so as to receive and conform to the cross-sectional shape of the strip 15. Although not necessarily so, the depth of the channel is preferably at least as great as the height of the workpiece when positioned as shown.

Mounted upon the bed 11 beyond one end of the forming die 14 is a clamp supporting block 17 which is adjustable longitudinally of the bed and adapted to be rigidly bolted thereto in proper position. Above the block 17 is an inclined platform 18 pivoted at 19 to the outer end of the block and supported in the desired angular position by means of one or more adjusting screws 20 which may be adjusted vertically to vary the tilt of the platform. Mounted in fixed position on the platform 18 is a clamp 21 carrying a series of four jaw members 21a shaped in common to receive one end of the workpiece 15. These jaws are slideable in one direction or the other in the usual manner along inclined interior surfaces of the clamp 21 so as to clamp or release the workpiece and are carried by a shiftable holder 21b secured to a piston rod 22 (see Fig. 6) which in turn is secured to a piston 23 slideable within an air cylinder 24.

The clamp 21 with its clamping or gripping jaws 21a, above described, provides a fixed means for clamping and holding one end of the workpiece 15 during the bending or forming operation. The opposite end of the workpiece is adapted to be rigidly clamped by means of a clamping device 25 carrying clamping or gripping jaws similar to the clamping device 21. The jaws of the clamping device 25 are shiftable longitudinally in order to grip or release the work by means of a holder 25a secured to a piston rod 26 which in turn is connected to a piston 27 shiftable within an air cylinder 28. This cylinder is pivoted at its outer end at 28a to a bracket 29 rigidly mounted on a platform 30. The platform 30 together with the clamping device 25 secured thereto extends between the spaced upright sides 31 of a bifurcated block, and the clamp 25 is pivoted or trunnioned in the upper ends of this block at 32. By this construction the clamping device 25 as well as the platform 30 and parts mounted thereon are adapted to pivot or swing about a horizontal axis formed by the pivots or trunnions 32.

The bifurcated block 31, which pivotally supports the work clamp 25 and its pneumatically operating mechanism, is rigidly secured to the upwardly projecting arm of a bell crank lever 33 which is fulcrumed or trunnioned intermediate its ends at 34 on the upright side portions 10a and 10b of the supporting frame 10. The lower arm 33a of this lever lies between the frame members 10a and 10b below the bed of the machine and is pivotally connected at 35a to a clevis 35 secured to the outer end of a piston rod 36 connected to a piston 37 (see Fig. 5) slideable within a hydraulic cylinder 38. The cylinder 38, as shown in Fig. 2, is pivotally mounted by means of trunnions at 39 on the upright sides of the frame 10, this construction permitting the hydraulic cylinder 38 to swing about a horizontal axis during the bending operation.

The mechanism by which the work clamp devices 21 and 25 are pneumatically operated is illustrated diagrammatically in Fig. 6. Mounted on the floor or supporting base for the machine and arranged side by side are a pair of conventional four-way air valves 40 and 40a. Since the piston and cylinder mechanism for each of the

clamp devices is controlled in the same manner, a description of the circuit for one thereof will suffice for both. Air under pressure from a suitable source of supply is introduced into each valve 40 and 40a through pipes 41 communicating with a main air inlet supply pipe or conduit 42. A pipe line 43 extends from each valve to the outer end of the cylinder 28 or 24 at a point behind the piston therein. A second pipe line 44 extends from the valve and communicates with the opposite end of the cylinder. Also extending from each valve is an air exhaust pipe 45. Each valve is operated by means of a pair of foot pedals 46 and 47. When the pedal 46 is depressed air under pressure entering the valve through pipe 41 will be diverted through pipe 43 into the outer end of the cylinder thereby forcing the piston inwardly to release the clamp. Air will be exhausted during this movement of the piston through pipe 44 and thence through the valve to the atmosphere through pipe 45. The reverse operation will take place when the pedal 47 is depressed to cause air under pressure to flow through line 44 into the inner end of the cylinder thereby forcing the piston outwardly to operate the work clamp and, hence, clamp the end of the strip 15.

The mechanism for controlling the hydraulic cylinder and piston mechanism 37, 38, which in turn operates the bell crank lever 33, is illustrated more particularly in Fig. 5. Oil or other hydraulic medium contained within a supply tank 48 is drawn from the tank through pipe 49 by a hydraulic pump 50 of conventional construction driven from an electric motor 51. The pump delivers fluid under pressure through pipe 52 to a suitable pressure control valve 53 provided with an adjusting screw 54 which may be adjusted to give the desired pressure setting as indicated by the reading on a pressure gauge 55. Oil under pressure corresponding to the setting made by the pressure control adjusting screw 54 is delivered from the valve 53 through pipe 56 to a four way spring control valve 57 of conventional type, this valve being operated manually by a control handle 58 so as to control the direction of flow of the hydraulic medium into and out of the valve in accordance with the direction in which the piston 37 is to be shifted within the cylinder 38.

Communicating with the valve 57 is a pipe line 59 which is connected to a pipe or conduit 60 leading to a one-way check valve 61 which is adapted to open when the pressure is in the direction of the arrows and permit the fluid to flow through the check valve. The pipe 59 is extended at 62 to communicate with a needle valve 63 controlled by means of an adjusting handle 63a. Fluid under pressure passing through the check valve 61 flows through a pipe 64 into pipe line 65 communicating with the needle valve 63 and also with the cylinder 38 at the head side of the piston 37. Thus when the fluid under pressure enters the cylinder through line 65 it will force the piston 37 outwardly. During this operation fluid will be exhausted from the opposite end of the cylinder through a pipe line 66 communicating with a check valve 67 and also with a pipe 68 leading to a one-way volume control valve 69 of conventional construction. Fluid exhausted from the cylinder through pipe 66 is blocked by the check valve 67 and, hence, flows through pipe 68 into the valve 69 and is metered thereby in order to control the speed 70 of the stroke of piston 37. The valve 69 may be

adjusted or set in order to vary the volume of liquid adapted to flow through the valve from pipe 68 by means of an adjusting handle 70, the proper setting being indicated by the reading on the dial of the valve. Thus, any desired speed of travel of the piston 37 may be obtained by properly adjusting or setting the volume control valve 69 through handle 70. From this valve the fluid is returned through pipe line 71 to the four-way valve 57. The pipe 66 communicates through check valve 67 with a by-pass pipe or conduit 72 leading into the pipe line 71. With the four-way valve 57 set so that fluid under pressure will flow in the direction of the arrows, thereby forcing the piston 37 outwardly, the return flow of fluid through line 71 will pass through the valve 57 and thence through return line 73 into the supply tank 48.

It will be readily understood from the foregoing and from a consideration of Fig. 5 that return travel of the piston 37 in the opposite direction will be achieved by manipulating the handle 58 to set the four-way valve 57 so as to cause fluid from the pump 50 to be delivered from line 56 into pipe line 71. When the flow is in this direction the fluid will be blocked at valve 68 and, hence, will flow through pipe 72, opening check valve 61, and thence will flow through line 66 into the outer end of the cylinder 38. As the piston is retracted fluid will be exhausted from the opposite end of the cylinder through line 65 past needle valve 63 into pipe 62 and thence through pipe 59 to the four-way valve 57, passing out of this valve through exhaust line 73. The pressure of the fluid passing through line 65 opposite to the direction of the arrows will close the check valve 61. The speed of the return stroke of the piston 37 will be governed by the setting of the needle valve 63 and the restriction offered thereby to the flow of fluid from line 65 past the needle valve into line 62.

From the foregoing it will be seen that outward motion of the piston 37 and piston rod 36 will swing the bell crank lever 33 about its fulcrum at 34 thereby swinging the upper arm of the bell crank and the carrier block 31 outwardly or away from the end of the forming die 14. Since one end of the workpiece 15 is rigidly secured in the clamp 25 carried by block 31, and since the opposite end of the workpiece is held in fixed position by the clamp 21, outward swinging motion of the upper end of the bell crank 33 will place the workpiece or strip in tension and exert a stretching action thereon.

In using the machine herein illustrated as exemplifying one embodiment of the invention the bar or strip 15, which may be of any suitable metallic material, such as aluminum alloy, is first bent or preformed to the approximate shape of the die so that it may be placed over the upper surface of the die 14 with the ends bent down sufficiently so as to permit them to be inserted into the jaws of the clamps 21 and 25. These jaws at this time will have been opened by operation of the pneumatic mechanism through depression of pedals 46 as previously described and particularly shown in Fig. 6. After the ends of the strip or workpiece 15 have been inserted into the clamps the operator depresses the pedals 47 causing the pistons 23 and 27 to move outwardly and thereby firmly clamping or gripping the ends of the workpiece. Before the forming operation commences the strip or workpiece is positioned on the die so that its apex 75 for moving said last named jaws, supporting

will overlie either one or the other or both of the inclined or tapered sides of the forming groove or channel 16. With the strip properly positioned and clamped at opposite ends the control handle 58 is manipulated to shift the mechanism of four-way valve 57 from neutral to a position in which the hydraulic medium from the pump 50 is forced through the valve into pipe line 59. With the flow in the direction of the arrows in Fig. 5 the piston 37 will be forced outwardly in cylinder 38 thus swinging the bell crank lever 33 and shifting the block 31 away from the end of the die 14. The rate of travel of the block as well as the clamp 25 will be governed as desired by adjusting the volume control valve 69. The distance that the clamp travels and, hence, the extent to which the work strip is stretched may be ascertained by reference to the reading given by a fixed pointer 75 on a scale carried by the block 31.

As the clamp 25 moves away from the end of the die it travels outwardly and downwardly in an arcuate path centered at the pivot 34 of the bell crank. As this operation proceeds the work strip 15 is progressively stretched and at the same time drawn downwardly into the forming channel 16. This operation is possible by reason of the fact that the apex of the angle piece engages one or the other sloping side of the channel and slides or is cammed down into the bottom of the channel as the work strip is drawn down over the die. The combined stretching and bending operation draws the strip uniformly into the irregularly shaped channel and causes it to permanently assume a configuration corresponding to the longitudinal configuration of the channel. Upon completion of the operation the pedals 46 are depressed to release or open the clamps 21, 25 and permit withdrawal of the finished strip. Thereafter the hydraulic mechanism will be operated to return the bell crank lever to its starting position.

It will be noted that the construction and arrangement of the operating mechanism for shifting the clamping device 25 during the stretch-bending operation are such as to enable substantial portions of this mechanism to be positioned below the clamping device 25 and housed in the space between the upright frame members 10a and 10b, thus providing a very compact construction in which the space occupied by the machine is reduced to a minimum. In the preferred construction, therefore, the bell crank lever 33 is pivotally mounted at 34 below the clamping device 25 and toward the center of the machine as seen in Fig. 1. By extending the arm 33a of the lever downwardly, as shown in dotted lines in Fig. 1, the hydraulic cylinder 38 and its pivotal connection at 35a with the lever arm 33a may also be positioned below the clamping device and toward the center of the machine, thus enabling maximum utilization of the space below the bed 11 and considerably reducing the overall length of the machine.

65 I claim:

1. In a bending machine, a forming die having an upwardly facing forming groove, a clamping device supported at one end of said die and having jaws movable to grip or release one end of a metal strip to be stretched in said groove, fluid actuated means for moving said jaws, a second clamping device at the opposite end of said die and having jaws movable to grip or release the opposite end of the strip, fluid actuated means

70 for moving said last named jaws, supporting

means for said second clamping device and last named fluid actuated means, a swinging member pivotally mounted intermediate its ends and having an articulated connection at its upper end with said supporting means, and fluid actuated means pivotally connected to the lower end of said member for swinging said member to move said second clamping device relatively to the first clamping device to stretch said strip; the pivotal mounting of said swinging member, said last named fluid actuated means and its pivotal connection, each being positioned below said second clamping device and toward the center of the machine.

2. In a bending machine, a forming die having an upwardly facing forming groove, a clamping device supported at one end of said die and having jaws movable to grip or release one end of a metal strip to be stretched in said groove, fluid actuated means for moving said jaws, a second clamping device at the opposite end of said die and having jaws movable to grip or release the opposite end of the strip, fluid actuated means for moving said last named jaws, supporting means for said second clamping device and last named fluid actuated means including a swinging bell crank lever pivotally mounted intermediate its ends and to the upper end of which said supporting means is pivoted, and means pivotally connected to said lever for swinging the lower end of said lever in one direction to move said second clamping device in the opposite direction and thereby stretch said strip, the pivotal mounting of said bell crank lever, said last named means and its pivotal connection with said lever, each being positioned below said second clamping device and toward the center of the machine.

3. In a bending machine, a forming die having an upwardly facing forming track to receive a metal strip to be bent, a clamping device at one end of said track and having jaws movable to grip and release one end of the strip, fluid actuated means for moving said jaws, a second clamping device at the opposite end of the track and having jaws movable to grip and release the opposite end of the strip, fluid actuated means for moving said last named jaws, a swinging lever pivotally mounted intermediate its ends, a support for said second clamping device and said last named fluid actuated means pivotally mounted on the upper end of said lever, and fluid actuated means pivotally connected to the lower end of said lever for swinging said end in one direction thereby to move said second clamping device in the opposite direction relatively to the first clamping device; the pivotal mounting of said lever, said last named fluid actuated means and its pivotal connection, each being positioned below said second clamping device and toward the center of the machine.

4. In a bending machine, a forming die having an upwardly facing forming track to receive a metal strip to be bent, a clamping device at one end of said track and having jaws movable to grip and release one end of the strip, a tiltable vertically adjustable support for said device, fluid actuated means for moving said jaws, a second clamping device at the opposite end of the track and having jaws movable to grip and release the opposite end of the strip, fluid actuated means for moving said last named jaws, a swinging lever pivotally mounted intermediate its ends, a support

for said second clamping device pivotally mounted on one end of said lever, and fluid actuated means pivotally connected to the opposite end of said lever for swinging said end in one direction thereby to move said second clamping device in the opposite direction relatively to the first clamping device; the pivotal mounting of said lever, said last named fluid actuated means and its pivotal connection, each being positioned below said second clamping device and toward the center of the machine.

5. In a bending machine, a vertically arranged forming die having an upwardly facing forming surface to receive a metal strip to be bent and stretched, a pair of clamping devices at opposite ends of the die, each device having movable jaws adapted to grip and release one end of the strip, means for operating the jaws of each clamping device, a swinging bell crank lever pivotally mounted intermediate its ends, a support for one of the clamping devices and its jaw operating means pivotally connected to the upper end of said lever, and means connected to the lower end of the lever for swinging the same to move said last mentioned clamping device relatively to the other clamping device; the pivotal mounting of said lever, said last named means and its connection to the lever, each being positioned below said last mentioned clamping device and toward the center of the machine.

6. In a bending machine, a vertically arranged forming die having an upwardly facing forming surface to receive a metal strip to be bent and stretched, a pair of clamping devices at opposite ends of the die, each device having movable jaws adapted to grip and release one end of the strip, means for operating the jaws of each clamping device, a swinging bell crank lever pivotally mounted intermediate its ends, a support for one of the clamping devices and its jaw operating means pivotally connected to the upper end of said lever, a vertically adjustable support for the other clamping device and its jaw operating means, and means connected to the lower end of the lever for swinging the same to move said first named support and the clamping device carried thereby relatively to the other clamping device; the pivotal mounting of said lever, said last named means and its connection to the lever, each being positioned below said last mentioned clamping device and toward the center of the machine.
